US00D619265S

(12) **United States Design Patent**
Livengood et al.

(10) **Patent No.:** **US D619,265 S**
(45) **Date of Patent:** **** Jul. 6, 2010**

(54) **PATIENT SUPPORT CART**

(75) Inventors: **Joseph C. Livengood**, Fort Collins, CO (US); **Amy L. Livengood**, Fort Collins, CO (US); **Justin M. Nittman**, Longmont, CO (US); **Barry T. Phillips**, Fort Collins, CO (US)

(73) Assignee: **Livengood Engineering, Inc.**, Fort Collins, CO (US)

(**) Term: **14 Years**

(21) Appl. No.: **29/350,539**

(22) Filed: **Nov. 18, 2009**

Related U.S. Application Data

(62) Division of application No. 29/325,581, filed on Oct. 2, 2008.

(51) **LOC (9) Cl.** **24-01**

(52) **U.S. Cl.** **D24/185**

(57) **CLAIM**

The ornamental design for a patient support cart, as shown and described.

DESCRIPTION

FIG. 1 is a front perspective view of an embodiment of our design, wherein the top portion of the patient support cart is being claimed solely;

FIG. 2 is a top plan view thereof;

FIG. 3 is a bottom plan view thereof;

FIG. 4 is a right elevation view thereof;

FIG. 5 is a front elevation view thereof;

FIG. 6 is a left elevation view thereof; and,

FIG. 7 is a rear elevation view thereof.

The dashed lines shown in the figures represent environment and form no part of the claimed design.
